UNITED STATES PATENT OFFICE.

JOHN F. O'CONNOR, OF CHICAGO, ILLINOIS, ASSIGNOR TO WILLIAM H. MINER, OF CHAZY, NEW YORK.

ANTIFRICTION-BEARING.

1,857,797.

Specification of Letters Patent.

Patented Nov. 2, 1920.

Application filed November 22, 1918. Serial No. 263,663.

To all whom it may concern:

Be it known that I, JOHN F. O'CONNOR, a citizen of the United States, residing at Chicago, in the county of Cook and State of Illinois, have invented a certain new and useful Improvement in Antifriction-Bearings, of which the following is a full, clear, concise, and exact description, reference being had to the accompanying drawings, 10 forming a part of this specification.

This invention relates to improvements in anti-friction bearings.

The object of the invention is to provide a simple and efficient, self-centering anti-friction bearing of the rocker type and more particularly adapted for use as a side bearing on railway cars.

In the drawing forming a part of this specification, Figure 1 is a vertical, sectional view taken through the body and truck bolsters of a car and showing my improvements in connection therewith. Fig. 2 is a vertical, sectional view taken substantially on the line 2—2 of Fig. 1. And Fig. 3 is a top plan 25 view of the side bearing, parts being broken away in order to get the figure on the drawing.

In said drawing, 10 denotes the under portion of a body bolster of a car and 11 the upper face of a truck bolster. As shown, my improved side bearing is attached to the truck bolster and comprises, broadly, two elements, *i. e.*, a housing A and the anti-friction element proper B.

The housing or base casting A is of hollow formation and has a plurality of flanges 12 at the bottom by which it is adapted to be riveted to the truck bolster. The housing is of generally rectangular formation as shown in plan in Fig. 3 and has vertical end walls 13—13 and side walls 14—14. Each side wall 14 is formed on its interior face with a convex bearing surface, as indicated at 15, and from each end of said convex bearing surface 15 extends a shoulder or wall 16 arranged at an angle of approximately 45° to the vertical. The bearing ledge 15 is suitably braced by the portion 17 of the side wall and ribs 18—18. Each end wall 13 is provided at its upper edge with an overhanging flange 19 adapted to coöperate with the element B to limit its rocking movement, as hereinafter explained. The side walls of

the housing A may be cut away near the bottom thereof, as indicated at 20, to permit 55 foreign matter to be washed out.

The anti-friction element B is in the form of a pendulum, broadly speaking. It is formed at its upper portion with a curved surface 21 adapted to engage with the body 60 bolster 10. The element B is laterally extended so as to form flat bearing surfaces or trunnions 22—22 on each side thereof, said flat trunnions resting upon the respective convex bearing ledges 15, as clearly indicated in Fig. 1. The element B is of reduced width beneath the trunnions and has a depending weighted section 23, there being a slight clearance between the depending section 23 and portions 17 of the side walls so 70 that the anti-friction element will be prevented from getting twisted within the housing. The upper portion of the element B has oppositely and upwardly inclined flat sides, as indicated at 24—24, and the depending section 23 has also flat faces 25—25 for the purpose hereinafter described. 75

The normal position of the parts is as shown in Fig. 1 in full lines. When the side bearing is brought into action and assuming 80 that the body bolster 10 moves to the left as viewed in Fig. 1, the element B will be rocked to the position shown by dotted lines. That is, the element B will have its flat trunnions 22 rolled around the convex bearing 85 ledges 15 and this action will be continued until the flat face 24 engages with the corresponding inclined wall 16 of the housing and the flat face 25 of the depending section engages with its corresponding overhanging 90 flange 19 of the housing, by which two factors the rocking movement is limited. Upon release of the actuating pressure, it is evident that the element B will automatically 95 return to normal because of the unbalanced position of the rocker, gravity acting to restore the balance.

From the preceding description, it will be seen that the side bearing involves only one movable element which can be easily made 100 in the form of a casting as can also the housing, so that the entire bearing is one of comparatively small manufacturing expense; no springs or other elements likely to easily get out of order are required; and the bearing 105 offers great strength since a large part of the

anti-friction element is under direct compression and bending moments are minimized.

I claim:

- 5 1. In an anti-friction bearing, the combination with a housing having curved bearing ledges, of a rocker carried by said housing, said rocker having a curved bearing surface and provided also with trunnion extensions, said trunnion extensions having flat bearing faces coöperable with said curved bearing ledges, the rocker being eccentrically weighted and adapted to be automatically returned to normal position under the influence of gravity.
- 10 2. In an anti-friction bearing, the combination with a housing, of a rocker having flat faced trunnions, said housing having curved bearing seats on said housing for said flat faced trunnions, the center of weight of the rocker being normally below the point of contact between said trunnions and said bearing seats.
- 15 3. In an anti-friction bearing, the combination with a housing having convex bearing seats on opposite sides thereof, of a rocker disposed within said housing and having flat bearing surfaces at each end thereof coöperable with said convex bearing seats, and coöperating means on said

rocker and housing to limit the rocking movement of the rocker.

4. In an anti-friction bearing, the combination with a hollow base casting adapted to be secured to the truck bolster of a car, 35 said base casting being provided on the interior thereof with curved bearing seats, of a pendulum rocker having flat bearing surfaces coöperable with said curved bearing seats, and means for limiting the rocking 40 movement of the rocker.

5. In an anti-friction bearing, the combination with a hollow base casting adapted to be secured to a truck bolster, said base casting being provided on the interior 45 thereof with opposed convex bearing surfaces and inclined walls adjacent said bearing surfaces, of a rocker having flat faced trunnions on each side thereof coöperating with said convex bearings of the base casting, said rocker having also flat faces normally inclined from the vertical and adapted to coöperate with said inclined walls of the base casting to limit the movement of the rocker with respect to the base casting. 50

In witness that I claim the foregoing I have hereunto subscribed my name this 1st day of Nov. 1918.

JOHN F. O'CONNOR.
